UNITED STATES PATENT OFFICE

NORMAN L. SNOW, OF NEW CANAAN, CONNECTICUT, ASSIGNOR TO DIAMOND POWER SPECIALTY CORPORATION, OF DETROIT, MICHIGAN, A CORPORATION OF MICHIGAN

BOILER CLEANER

Application filed November 26, 1923, Serial No. 677,165. Renewed May 12, 1931.

The invention relates to boiler cleaners and refers more particularly to boiler cleaners of that type having a rotary blower element through which the steam or the like is discharged upon the boiler tubes, and a hand operated chain for rotating the blower element. One of the objects of the invention is to provide a boiler cleaner of the above-mentioned type having means cooperating with the hand operated chain for automatically limiting its movement, thereby directing the attention of the operator to the fact that the blower element has been rotated through a predetermined angular travel which may be greater or less than 360° . A further object of the invention is the provision of a boiler cleaner having a common actuating member for rotating the blower element and opening and closing the valve which controls the admission of the steam or the like to the blower element.

With these as well as other objects in view, the invention further resides in the novel features of construction as more fully hereininafter set forth.

In the drawings:

Figure 1 is a side elevation of a boiler cleaner embodying my invention;

Figure 2 is an end view thereof partly in section;

Figure 3 is a cross section on the line 3-3 of Figure 2;

Figure 4 is a view similar to Figure 2, but showing a modified construction;

Figure 5 is a plan view of the outer end of the valve arm;

Figures 6 and 7 are respectively a side elevation and an end view of another modified construction.

In the construction of boiler cleaner shown in Figures 1, 2 and 3, 1 is the rotary blower element or pipe provided with a longitudinal series of nozzles for discharging jets of steam or the like upon the boiler tubes of the boiler.

This blower element is connected in the usual manner as by means of a swivel to the stationary supply pipe 2 in the upper end of which is located the valve 3 for controlling the admission of steam or the like to the blower element. The blower element is ro-

tated by the manual operation of the chain 4 which runs over the sprocket wheel or sheave 5, which sprocket wheel or sheave is operatively connected to the blower element by suitable reduction gearing such as the pinion 6 and the gear 7. The valve 3 is moved to open position by means of the pivotal lever 8 and the cam 9 rotatable with the blower element. As thus far described, the construction of boiler cleaner is usual for this type of boiler cleaner.

For the purpose of automatically calling the attention of the operator to the fact that the blower element has been rotated through a predetermined angular travel which may be greater or less than 360° depending upon the conditions, I have provided the stop 10 in the form of a multi arm wheel 11 upon the shaft 12 at one side of the chain 4 and so positioned that the outer ends of the arm 11 come into engagement with the chain. These outer ends, as shown particularly in Figure 3, are longitudinally slotted to form bifurcations 12' adapted to embrace the chain, but spaced apart a distance such that the balls 13 secured upon the chain at predetermined intervals, cannot pass therebetween. Two of the diametrically opposite extending arms have their outer ends curved in a direction opposite to that of rotation of the wheel, the radius of curvature being approximately equal to the radius of the balls so that the latter may fit in the former. The wheel is prevented from rotating in the opposite direction by means of the dog 14 having its nose engageable with the annular series of teeth 15 upon the hub of the wheel.

With this arrangement, the operator, upon pulling the chain 4 in the direction indicated by the arrow in Figure 2, rotates the blower element 1 and also actuates the valve 3. Furthermore, during the operation of the chain, the balls 13 come successively into contact with the upper sides of the bifurcations 12' of the arms of the stop wheel, and if the arms are straight, the balls move the arms downwardly to a point where the former slide off the latter, thereby effecting a step-by-step rotation of the stop wheel. However, as soon as a ball comes into con-

tact with an arm having an outer curved end, this ball while moving the arm downwardly is compelled to move laterally from the usual path taken by the chain until a point is finally reached where the stop wheel will actually hold the chain from further movement, thereby directing the operator's attention to the fact that the boiler cleaner has been operated for a predetermined length of time. When the movement of the chain has been stopped, the valve 3 is preferably closed. To operate the boiler cleaner for another predetermined period of time, it is necessary for the operator to first pull down on the opposite side of the chain to raise the ball engaging the curved arm to thereby disengage the ball therefrom. This is possible, by reason of the fact that the stop wheel is held from rotation in the reverse direction by means of the dog 14 engaging the teeth 15. As soon as the ball has been raised out of engagement with the curved arm, it will then swing laterally with the chain to its normal position whereupon as the operator pulls down upon the chain to move the same in the opposite direction as indicated by the arrow in Figure 2, the ball will slide over the outer end of the curved arm and the succeeding balls will successively engage and move the succeeding arms through predetermined arcs until a ball comes into engagement with the other curved arm and is held from further movement.

In the modified construction shown in Figures 4 and 5, the rotary blower element 16 is actuated by the chain 17 in the same manner as shown in Figures 1 and 2. The valve 18 for controlling the admission of the steam or the like to the blower element, is also moved to open and closed positions by means of the chain 17. This valve has secured thereto the arm 19 which extends into the path of the chain and is provided with the key-hole slot 20 at its outer end through which the same passes. The chain is provided with the series of balls 21 secured thereto at predetermined intervals and the enlarged portion of the key-hole slot 20 is of a size to permit these balls to pass therethrough, but the reduced portion of the key-hole slot is sufficiently narrow to prevent the balls from passing therethrough. Furthermore, the enlarged portion of the key-hole slot is located beyond the reduced portion, and as a consequence when the parts are in the position shown by full lines in Figure 4, the chain upon being pulled in the direction indicated by the arrow passes through the reduced portion of the key-hole slot until a ball comes into contact with the upper side of the arm, after which continued movement of the chain in the same direction compels downward swinging of the arm and consequent moving of the valve to closed position. When the arm reaches the position indicated

by dotted lines, the ball will then slide outwardly and downwardly upon the arm and pass through the enlarged portion of the key-hole slot, leaving the valve in closed position. To move the rotary element in the opposite direction and move the valve to open position, the chain is moved in the opposite direction, at which time it passes upwardly through the reduced portion of the key-hole slot until a ball comes into engagement with the underside of the arm, after which, the arm is swung upwardly to the position indicated by full lines when the valve is open. Upon continued movement of the chain in the same direction, the ball slides outwardly along the underside of the arm and passes through the enlarged portion of the key-hole slot, after which the chain may be moved in the same direction until rotation of the blower element is stopped.

Figures 6 and 7 disclose another modified construction of boiler cleaner in which 22 is the rotary blower element having nozzles through which steam or the like is discharged upon the boiler tubes. This blower element projects from the blower head 28 and is rotated by means of the chain 23 passing over the sheave 24, which latter is connected to the blower element by means of the pinion 25 and gear 26. 27 is the valve controlling the passage of steam or the like through the stationary supply pipe 28 to the blower head 28 and blower element 22.

In the present instance the valve is opened and closed upon actuation of the chain 23 in one direction. In detail, this valve has secured thereto the multi-arm wheel 29 having the arms 30, 31, 32 and 33 provided with outer bifurcated ends through which the chain is adapted to extend. This chain has secured thereto the enlargements or balls 34 which are so located that upon actuating the chain in the direction indicated by the arrow in Figure 7 the valve will be moved from closed to open position by a ball engaging the arm 30 rotating the multi-arm wheel 29 in a clockwise direction to a point where the ball will slide off the arm. At this time the valve is in open position and the arm 31 now occupies the position originally occupied by the arm 30. Upon continued actuation of the chain in the same direction, the succeeding ball 34 engages the arm 31 rotating the multi-arm wheel 29 in a clockwise direction to a position to close the valve, after which the ball slides off the arm. The spacing of the balls may be such that the blower element may be rotated any desired number of times while the valve is open and before it is closed. While, as shown, the multi-arm wheel is provided with four arms, it is apparent that the number of arms may be readily varied.

What I claim as my invention is:

1. In a boiler cleaner, the combination with the blower element and a valve for controlling the admission of steam or the like thereto, of a flexible member for actuating said blower element having an enlargement, and means cooperating with said enlargement for causing the actuation of said valve, said means including a slotted arm.
2. In a boiler cleaner, the combination with the blower element, of a valve controlling the admission of steam or the like to said blower element, and a flexible member operatively connected to actuate said blower element, said flexible member being provided at predetermined intervals along its length with means adapted to coact with said valve to actuate the latter.
3. In a boiler cleaner, the combination with the blower element, of a valve controlling the admission of steam or the like to said blower element, a flexible member for actuating said blower element, and means upon said valve and flexible member for actuating the former from the latter.
4. In a boiler cleaner, the combination with a blower element, of a valve for controlling the admission of steam or the like to said blower element, a flexible member for actuating said blower element provided with an enlargement, and an arm connected to said valve and provided with a slot through which said flexible member extends, the slot having a width less than that of said enlargement, whereby movement of said flexible member and enlargement is adapted to compel movement of said arm, said arm having provision for permitting the disengagement of said enlargement therefrom.
5. In a boiler cleaner, the combination with a movable blower element, of a valve controlling the admission of steam or the like to said blower element, a flexible member for actuating said blower element, and cooperating means upon said valve and flexible member for opening and closing the valve upon actuation of the flexible member to move the blower element a predetermined amount.
6. In a boiler cleaner, the combination with a rotatable blower element and a valve for controlling the admission of steam or the like thereto, of a flexible member for rotating said blower element, and means upon said valve and flexible member for successively opening and closing the valve upon movement in one direction of the flexible member.
7. In a boiler cleaner, the combination with a rotatable blower element, of a valve controlling the admission of steam or the like to said blower element, a flexible member for rotating said blower element, a multi-arm wheel connected to said valve for opening and closing the same, and means upon said flexible member engageable successively with the arms of said wheel upon movement of said flexible member in one direction to rotate said wheel a distance to successively open and close said valve.
8. In a boiler cleaner, the combination with the blower element and a valve for controlling the admission of a cleaning fluid thereto, of a flexible member for actuating said blower element having a projection and means cooperating with said projection for controlling the actuation of said valve.
9. In a boiler cleaner, the combination with a blower head, of a blower element mounted in the said blower head, a cleaning fluid supply pipe connected with said blower head, a flexible member connected to actuate the blower element and provided with an abutment, and a valve in said supply pipe along the length thereof at a point beyond the blower head, said valve having a portion projecting in the path of said abutment whereby the valve may be actuated by a movement of the flexible member.
10. In a boiler cleaner, the combination with a blower head, of a blower element mounted in the said blower head, a cleaning fluid supply pipe connected with said blower head, a flexible member connected to actuate the blower element, a valve in said supply pipe along the length thereof at a point beyond the blower head, said valve having a portion engageable by said member whereby the valve may be actuated by a movement of the member.
11. In a boiler cleaner, the combination with a blower element, of means for supplying cleaning fluid to said element, a valve controlling the supply of cleaning fluid to said element, a flexible member adapted to impart rotation to said element, and means spaced along said flexible member at predetermined intervals for successively opening and closing the valve for a continuous movement of the flexible member, the successive movements of the valve bearing a predetermined relation to the angular movement of the blower element.
12. In a boiler cleaner, the combination with a blower element, of a valve controlling the admission of cleaning fluid to said blower element, a flexible member for actuating said blower element and for effecting the unseating of the valve and means carried by the flexible member for directly indicating the position of the valve.
13. In combination a blower element, a valve for controlling the supply of cleaning fluid to said blower element, a lever for actuating the said valve, a flexible element for actuating the said blower element, and means carried by said flexible element engageable with said valve actuating lever upon a predetermined longitudinal movement of the said flexible element for actuating the said valve.
14. In a boiler cleaner, the combination

- with a blower element, of a valve controlling the admission of cleaning fluid to said blower element, a flexible member, means for actuating said blower element from said flexible member, and a mechanical connection between said valve and flexible member independent of said blower element actuating means for actuating the valve from the flexible member.
15. In a boiler cleaner, a rotatable blower member, a valve member for controlling the flow of cleaning fluid to said blower member, a movable flexible element, and means carried by said flexible element for controlling the actuation of one of said members.
16. In a boiler cleaner, a rotatable blower member, a valve member for controlling the flow of cleaning fluid to said blower member, and a movable flexible element having an enlargement arranged to control the actuation of one of said members.
17. In a boiler cleaner, the combination with a blower element and a valve for controlling the admission of steam or the like thereto, of a flexible member for actuating said blower element, and means cooperating with said flexible member for automatically limiting its movement.
18. In a boiler cleaner, the combination with a blower element adapted to discharge steam or the like and a valve for controlling the admission of steam or the like to said blower element, of a flexible member for actuating said blower element, said flexible member being provided with an enlargement, and an arm having a slot therein through which said flexible member extends, said slot having a width less than that of said enlargement, whereby movement of said flexible member is limited.
19. In a boiler cleaner, the combination with a rotary blower element and a valve for controlling the admission of steam or the like thereto, of a flexible member for operating said blower element, a rotatable stop member including an arm having a curved end provided with a slot through which said flexible member extends, and an enlargement upon said flexible member engageable with the curved end of said arm and held from passing through the slot therein, the curvature of said arm holding said enlargement from lateral movement of said arm.
20. In a boiler cleaner, the combination with a rotary blower element and a valve for controlling the admission of steam or the like therethrough, of a chain for actuating said blower element provided with a series of spaced enlargements, and a stop member for limiting the movement of said chain including a multi arm wheel having an arm with a curved outer end, all of said arms having slots therein engageable by the chain and of a width less than that of said enlargements, the arm having the curved end preventing

lateral disengagement of the enlargement in contact therewith and thereby limiting the movement of the chain.

21. In a boiler cleaner, the combination with a rotatable blower element, and a flexible member for rotating said blower element, of means cooperating with said flexible member and operable upon a predetermined movement thereof to lock said flexible member and blower element against further movement, said means being releasable to permit continued movement of said flexible member in the same direction upon a different movement of the flexible member.

22. In a boiler cleaner, a movable blower element, means including a flexible member operable upon continued movement in one direction to move said blower element in a predetermined direction, means operable upon a predetermined movement of the flexible member to lock the same against further movement in the said direction to lock said blower element against movement, said locking means being releasable upon movement of the flexible member in a second direction to permit movement of the flexible member and blower element in the said first mentioned directions.

23. In a boiler cleaner, a movable blower element, a valve for controlling the flow of cleaning fluid to said blower element, a flexible member for moving said blower element, and means on said flexible member operating upon movement of said flexible member in one direction to open said valve and upon movement of said flexible member in the other direction to close said valve.

24. In a boiler cleaner, a rotatable blower element, a valve for controlling the flow of cleaning fluid to the blower element, a flexible member for rotating the blower element, means providing an enlargement on said flexible member, and means cooperating with said enlargement operable upon movement of said flexible member in one direction to open said valve and operable upon movement of said flexible member in the other direction to close said valve.

25. In a boiler cleaner, a rotatable blower element, a valve operating in timed relation to the rotation of the blower element for controlling the flow of cleaning fluid to said blower element, a sheave wheel connected to said blower element for rotating the same, means including a flexible element engageable with said sheave for rotating said blower element, said flexible element being provided with an enlargement formed thereon, and means cooperating with the said enlargement for limiting movement of the said flexible element.

26. In a boiler cleaner, the combination with a rotatable blower pipe adapted to discharge jets of cleaning fluid, of a valve for controlling the supply of said cleaning fluid

to said pipe, means operable to actuate the said valve upon the rotation of the blower pipe, and means for rotating said pipe including a member fixed to rotate with the blower pipe, and a flexible operating member engageable with the first said member, and indicating means cooperating with said flexible member for indicating when the valve is in a position to shut off the supply of cleaning fluid.

27. In a boiler cleaner, the combination with a rotatable blower pipe adapted to discharge jets of cleaning fluid, of a valve for controlling the supply of said cleaning fluid to said pipe means operable to actuate the valve upon rotation of the blower pipe, and means for rotating said pipe, including a sheave and a chain operably engaging the sheave, and means located adjacent the path of the chain and cooperating with a predetermined portion thereof for indicating when the valve is in a position to shut off the supply of cleaning fluid to said pipe.

In testimony whereof I affix my signature.
